UNITED STATES PATENT OFFICE.

DENNIS C. DUCATT, OF SARANAC LAKE, NEW YORK.

TOY COASTER.

1,334,441.

Specification of Letters Patent. Patented Mar. 23, 1920.

Application filed June 6, 1919. Serial No. 302,306.

To all whom it may concern:

Be it known that I, DENNIS C. DUCATT, a citizen of the United States, residing at Saranac Lake, in the county of Franklin and State of New York, have invented certain new and useful Improvements in Toy Coasters, of which the following is a specification.

This invention relates to toys and more particularly to a toy coaster which may be employed either with wheels, or with runners for use on ice and snow.

One of the objects of the invention is to provide a toy horse mounted on a frame which may be ridden by children and which will be equipped with driving mechanism arranged to propel the toy when it is used as an ice or snow coaster.

A further object of the invention is to provide a device of this character which consists of comparatively few parts and is simple in construction, but durable and well adapted to withstand the rough usage to which devices of this character are ordinarily subjected.

For a full description of the invention and the advantages and merits thereof, reference is to be had to the following description and accompanying drawings, in which—

Figure 1 is a side elevation of the device constructed in accordance with my invention, parts being broken away to more clearly disclose the operative parts.

Fig. 2 is a section taken approximately on the line 2—2 of Fig. 1.

Fig. 3 is a detail section of a portion of the operating apparatus, and

Fig. 4 is a detail plan view of a portion of the steering device.

Referring to the drawings, wherein is illustrated the preferred form of my invention, in which like numerals of reference indicate like or corresponding parts throughout the several views, the main portion of the apparatus is in the form of a body of a toy horse, equipped with a saddle 2 upon which the rider may be seated. The front supporting standard 3 is provided with an axle 4 which, in the present instance is equipped with a front runner 5, and it will be obvious that the front steering wheel may be substituted for this runner if desired. The front standard is also provided with an upwardly extending king pin 6 projected through the body of the horse and ro-

tatably mounted so that the standard may be turned. The upper end of the king pin projects upwardly from the top of the body forwardly of the saddle 2 and carries a handle bar 7 which may be grasped by the rider to turn so that the forward runner may be turned to steer the device. Attached to the hind legs are the rear standards 8 which carry the rear axle 9, the ends of which receive the rear runners 10. These runners may also be removed so that wheels may be mounted on the ends of the axle when desired. The frame bars 11 are attached to the standards 8 and project forwardly beneath the body of the horse and have their forward ends joined to a projection 12 fixed to the body 1. These frame bars are equipped with a drive shaft 13 journaled in suitable bearings carried by the side bars and have their ends provided with the pedals 14 which may be engaged by the feet of the rider so that turning movement may be imparted to the drive shaft 13. Fixed to the drive shaft 13 is a sprocket 15 over which a chain 16 is trained and the shaft or rear axle 9 carries a sprocket 17 having the chain 16 trained thereover so that the rear axle may be driven when the sprocket is rotated. The rear axle 9 also carries a sprocket 18 engaged with a chain 19 which is also trained over a sprocket 20 on the counter shaft 21. The latter is supported in a rearwardly extending frame which is formed by the frame bars 22 which are equipped with bearings 23 having the ends of the shafts 21 journaled therein. Also mounted upon the shaft 21 is a wheel 24 the periphery of which is equipped with spikes or prongs 25 which are adapted to engage the ice or snow on the surface over which the device travels to drive the apparatus forwardly. The forward ends of the frame bars 22 are pivotally connected to the rear axle 9 so that the frame bars may be swung upwardly to raise the power wheel out of engagement with the ice or snow. This lifting operation is accomplished through the medium of a lift bar 26 attached to one of the bearings 23 and secured to a lever 27 pivoted to one of the hind legs of the horse as shown in Fig. 1. The pivot member 28 permits the lever 27 to swing, and the opposite end of the lever is connected by a pull rod 29 to an operating lever 30 pivoted as indicated at 31 on the side of the body and equipped with a latch member

32' whereby the lever may be held in the desired adjusted position. When the lever 30 is swung on its pivot, the pull rod 29, is actuated to swing the lever 27 on its pivot whereby the pull rod 26 may be actuated to raise or lower the power wheel 24. A coil spring 32 is secured to one of the hind legs and to the bar 26 so that the wheel is urged into the ground under normal conditions.

10 When in use as a coaster on ice or snow, the lever 30 will be pulled rearwardly so that the power wheel is urged into the surface of the ice or snow and the rider will actuate the pedals so that the chain driving mechanism will rotate the power wheel to drive the apparatus forwardly. It may be readily guided by turning the handle bar 7. Obviously when a hill is reached down which the device may freely coast, the lever 20 30 may be thrust forwardly so that the power wheel will be lifted out of engagement with the surface and the apparatus is then free to slide or coast down the hill. Inasmuch as the rear axle rotates when the 25 pedals are actuated it will be readily apparent that wheels may be mounted in place of the rear runners 10 so that the device may be employed on the surface of the ground. The foregoing description and accompanying drawings have reference to what 30 might be considered to be the approved or preferred form of my invention. I desire it to be understood that I may make such changes in the construction, combination 35 and arrangement of parts, materials, dimensions, et cetera, as may prove expedient and fall within the scope of the appended claims.

Having thus fully described my invention what I claim as new and desire to secure by Letters Patent, is:—

1. In a device of the class described, the combination of a toy horse, runner means provided for carrying said toy horse, a power wheel, means for connecting said power wheel to said toy horse, a lever fulcrumed at its center point upon said toy horse, a rod attached to one extremity of said lever and to said power wheel, a rod connected to the other extremity of said lever and means provided for pulling and pushing said last mentioned rod, whereby said power wheel may be lifted or lowered and means provided upon said first mentioned rod to normally force same downwardly.

2. In combination with a toy horse provided with runners, a bar pivotally connected to one of said runners, a power wheel connected to said bar, means for rotating said power wheel, a lever fulcrumed at its center point upon said toy horse, a rod connected to one extremity of said lever and connected to said power wheel, a spring having one end attached to said rod and its other end attached to said toy horse thereby normally pulling said rod downwardly, and means for manipulating said lever so as to pull or push said rod for lifting or lowering said power wheel.

In testimony whereof I affix my signature in presence of two witnesses.

DENNIS C. DUCATT.
